UNITED STATES PATENT OFFICE,

GANO S. DUNN, OF EAST ORANGE, NEW JERSEY, ASSIGNOR TO THE CROCKER-WHEELER ELECTRIC COMPANY, OF NEW JERSEY.

DESIGN FOR A FRAME FOR DYNAMOS.

SPECIFICATION forming part of Design No. 27,098, dated May 25, 1897.

Application filed March 25, 1897. Serial No. 629,281. Term of patent 14 years.

To all whom it may concern:

Be it known that I, GANO S. DUNN, a citizen of the United States, residing at East Orange, county of Essex, State of New Jersey, have invented a new and original Design for a Frame for Dynamo-Electric Machines, of which the following is a specification.

In the accompanying drawings, which form a part of this specification, Figure 1 is a perspective view of the frame. Fig. 2 is a front view; and Fig. 3 shows a sectional view, the section being taken on the line X X of Fig. 2.

The characteristic feature of the design consists in the general configuration of the 15 annular frame or yoke A, provided with in-

ward projections B. This configuration consists in the rounded outer edges d d and the inwardly-projecting flanges f f.

What I claim as my invention, and desire to secure by Letters Patent of the United States, is—

The design for the frame of a dynamo-electric machine, substantially as herein shown and described.

Signed by me at Ampere, Newark, New Jersey, this 22d day of March, 1897.

GANO S. DUNN.
